UNITED STATES PATENT OFFICE.

WILLIAM HALKET AND WALLACE L. VAN VALKENBURG, OF HOLYOKE, MASSACHUSETTS.

MAGAZINE CLIP.

Application filed March 26, 1925. Serial No. 18,399.

This invention relates to improvements in clips for supporting magazines or other like articles, as several sheets of papers which it is desired to clamp or secure together. It is often desirable to support or hang magazines or papers on a line or hook in store windows or book stands for exhibition purposes.

An object of the present invention is to provide a supporting clip that is so constructed that its clamping jaws may be opened or separated a greater distance than clips which are now in use. This is accomplished by making or forming the pivot supporting ears of the movable jaw very much longer than the pivot supporting ears of the fixed jaw, whereby the arc through which the movable gripping jaw moves into its open position is very materially increased.

A further object is to provide a flat or leaf spring which is located between the jaws of the clip and which spring is formed with integral pivot projections on its opposite side edges which enter the pivot openings of the ears. The fixed jaws is formed with a hook-shaped extension for supporting or hanging the magazine or other article. The hook further serves as a support for the first or second finger for the user and the thumb for depressing the movable jaw.

These and other objects will appear in the body of the specification and drawings and will be particularly pointed out in the appended claims.

Referring to the drawings:

Fig. 1 is a perspective view of the clip shown supporting a magazine.

Fig. 2 is a side elevational view of the clip with the jaws in a closed position.

Fig. 3 is a side view with the movable jaw in an open position.

Fig. 4 is a sectional view on the line 4-4 of Fig. 2.

Fig. 5 is a detail perspective view of the flat or leaf spring showing the pivots and

Fig. 6 is a perspective view of a spring formed from wire.

Referring to the drawings in detail:

1 designates a supporting rod or line, 2 the fixed plate number having the hook extension 3, 4 the upturned jaw portion that is formed with teeth on its upper edge. 6 and 7 are the oppositely located upturned pivot ears that are integral with the plate

member 2. They are formed with the pivot receiving openings 8 and 9. 10 designates the upper or movable plate which is formed with the downwardly extending, integral, and pivot receiving ears 11 and 12. Its forward end is formed with the downwardly extending jaw 13 having the gripping teeth which mesh with the teeth on the lower upturned jaw 4. The rear end portion of the upper movable plate 10 is formed with a slightly upturned portion 14 for the purpose of affording a convenient support for the thumb of the user when this movable member is moved into its open position, for receiving or releasing a magazine.

Interposed between the upper and lower plate members 10 and 2, and between the ears is a flat or leaf spring 15 that is bent intermediate its ends at 16 to form the upper and lower end portions 17 and 18 which, as shown, rest against and engage the inner surfaces of the plate members 10 and 2. 19 and 20 designate oppositely located integral projections on the side edges of the portion 18 of the spring 15. These integral projections serve as the common pivots which are located in the openings 8 and 9 of the ears 6 and 7 and in the openings 11' and 12' of the ears 11 and 12, whereby the spring 15 serves the double purpose of normally retaining the jaws 4 and 13 of the plate members 2 and 10 closed, and providing pivots for these two members.

By reason of the ears 11 and 12 of the movable plate 10 being very much longer than the ears 6 and 7 of the arc or angle through which the upper plate 10 can be moved is materially increased. This is clearly shown in Fig. 3 by the wide space between the jaws 4 and 13, whereby a thick magazine or a large number of papers may be clamped together. A clamped magazine is indicated in Fig. 1 at 21. This wide opening of the jaws is accomplished by reason of the fact that the openings in the two sets of ears are spaced or located different distances from the upper and lower plate members, or, in other words the ears 11 and 12 are longer than the ears 6 and 7 thus providing greater lever action and a wide opening between the meshing jaws.

Fig. 6 illustrates a spring that is formed of wire which is bent on itself at 22 and having the upper parallel portions 23 and 24, the return bends at 25 and 26, the lower

parallel portions 27 and 28 and the pivot end portions 29 and 30 of the end extensions 31 and 32. The pivots 29 and 30 enter the aligned openings of the ears in the same 5 manner as the projections 19 and 20 of the leaf spring 15. The upper and lower parallel portions 23 and 24, and 27 and 28 engage the inner surfaces of the plates 10 and 2 as already described in connection with 10 Figs. 1, 2, 3 and 4.

Further it should be particularly observed that the upper and lower plate members are each provided with a handle portion; indicated at 3 and 14 whereby, when these portions are gripped the jaws may be opened. 15 The lower member 2 is, in practice, not movable, as it is gripped by the operator. The member 10 is the movable one.

What we claim is:

- 20 1. An article holding clip comprising in combination, an upper and lower plate member, each having integral upturned jaw portions, which engage, each member having integral oppositely extending ears with openings therein, which register with each other, a spring located between the plate members and having extensions on its opposite edges which extensions are located in the registering openings of the ears of the said members 25 to pivotally connect the members together, the ears of the upper member being substantially longer than these of the lower mem-

ber and the pivot openings in the ears of the upper member being located a greater distance from its plate than are the pivot 30 openings of the lower member, whereby when the upper member is operated the jaws will be widely separated.

2. An article holding clip comprising in combination, an upper and lower plate member, 40 each having integral upturned jaw portions, which engage, each member having integral oppositely extending ears with openings therein, which register with each other, a spring located between the plate members 45 and having extensions on its opposite edges which extensions are located in the registering openings of the ears of the said members to pivotally connect the members together, the ears of the upper member being substantially longer than these of the lower member 50 and the pivot openings in the ears of the upper member being located a greater distance from its plate than are the pivot 55 openings of the lower member, the upper member having an upwardly extending rear end portion and the lower member having a downwardly extending curved or hook-portion, whereby when the upper member is operated the jaws will be widely separated.

Signed by us at Holyoke, Mass.
